UNITED STATES PATENT OFFICE.

WILLIAM T. CARNES, OF KANSAS CITY, MISSOURI, ASSIGNOR TO CARNES ARTIFICIAL LIMB COMPANY, OF KANSAS CITY, MISSOURI, A CORPORATION OF MISSOURI.

ARTIFICIAL ARM.

1,046,967.

Specification of Letters Patent.

Patented Dec. 10, 1912.

Application filed March 18, 1912. Serial No. 684,468.

To all whom it may concern:

Be it known that I, WILLIAM T. CARNES, a citizen of the United States, residing at Kansas City, in the county of Jackson and 5 State of Missouri, have invented certain new and useful Improvements in Artificial Arms; and I do hereby declare the following to be a full, clear, and exact description of the invention, such as will enable others skilled 10 in the art to which it appertains to make and use the same, reference being had to the accompanying drawings, and to the letters of reference marked thereon, forming part of this specification.

15 My invention relates to artificial limbs of the type illustrated and described in U. S. Letters-Patent No. 760,102, dated May 17, 1904; and U. S. Letters-Patent No. 999,484, dated August 1, 1911, issued upon my applications, and has for its object the constructing of mechanism by which an operating cord, which in the above mentioned 20 patents was used for operating the fingers of the artificial hand, may be used for operating the elbow joint of an artificial arm in cases where the amputation is above the elbow joint, the mechanism which is the subject of this invention being so contrived that by means of a single operating cord, 25 the fingers of the artificial hand may be opened and closed.

The features of my invention are herein-after set forth and fully described and illustrated in the accompanying drawings, in 30 which:

Figure 1, is a back view of a supporting and operating harness, and artificial arm in place upon the shoulders and stump of a wearer; the harness shown in this figure 35 being the same as that shown, described and claimed in my pending application filed June 7, 1911, Serial No. 631,806, and forms no part of the present invention. Fig. 2, is a front view of the same. Fig. 3, is a 40 front view of my artificial arm, having the upper end thereof broken away, and showing the fore-arm in section so as to disclose the reversing mechanism therein, and having the hand member thereof broken away. Fig. 4, is a side view of the same. Fig. 5, is 45 an enlarged side view in elevation of the reversing mechanism removed from the fore-arm. Fig. 6, is an end view of the same looking in the direction of the arrow 50 in Fig. 5. Fig. 7, is an end view of the 55

ratchet wheel removed from the reversing mechanism. Fig. 8, is a side view of the same. Fig. 9, is a side view of the wrist and hand members with portions thereof broken away.

60 In these drawings A, indicates the fore-arm member of my improved artificial arm, A', indicates the upper or socket member thereof adapted to fit and receive the stump of an arm which has been amputated above 65 the elbow joint, A², indicates the wrist member, A³, indicates the wrist joint, and A⁴, indicates the hand member of my improved artificial arm, B indicates a strap (see Fig. 1) passing diagonally upward across the 70 back and over the shoulder opposite to the amputated arm and downward across the front of said shoulder and backward under that arm (see Fig. 2) and then upward across the back and over the shoulder of the 75 amputated arm and down in front of the amputated arm, ending in a loop B', (see Fig. 2) said strap B, at the back of the wearer being also provided with a terminal loop B², (see Fig. 1) secured to the strap B, 80 and passing therefrom diagonally downward across the chest is a strap C, terminating in a loop C', adjacent to the artificial arm (see Fig. 2) the balance of the harness shown in Figs. 1 and 2, and its purpose, is 85 fully shown and described in the aforesaid co-pending application, and further description thereof in this application is not deemed necessary.

90 From the terminal loop B², at the back of the arm member A', an operating cord D, extends around a pulley d, into the arm member A', and through the same to the opposite side thereof where it passes out around the pulley d', and around the lower 95 end of the arm member A', and down into and is secured to the fore-arm member A, (see Figs. 3 and 4) the fore-arm member A, is hinged upon the arm-member A', by means of an elbow-pivot a, so that when it 100 is desired to bend the elbow joint, an upward and forward movement of the shoulder opposite to the amputated arm will, by means of the strap B, pull on the cord D, and cause the fore-arm member to swing forward and upward on the pivot a. Within the fore-arm member A, I mount a shaft E, upon suitable supports e, secured to the inner wall of the shell of the fore-arm member. Upon this shaft E, (see Fig. 6) is 105 110

secured an arm E', having on its outer end the ears E², and E³, and having also between the ears E², and E³, recesses e', (see Fig. 5) tapped therein. The ears E², extending entirely across the end of the arm E', and extending below the lower edge thereof as shown by broken lines in Fig. 5.

Between the ears E², and E³, I pivot rocking-ratchets F and F', by means of the 10 pivot f, and underneath one end of the rocking-ratchets F and F', within the recesses e', I place springs f'.

Between the lower ends of the ears E², on the arm E', I mount a ratchet-wheel G, having a hub on each side thereof extending to the inner faces of the ears E², upon a pivot g. The ratchet-wheel G, is provided with six teeth, and the hub G', thereof on each side of the ratchet-wheel G, is provided 15 with three notches g', the notches g', in the hub G', being staggered with relation to the notches g', on the opposite side of the ratchet-wheel; the notches g', being adapted 20 to receive the lower ends of the rocking- ratchets F and F', alternately on each side 25 of the ratchet-wheel G. Secured upon the inner surface of the shell of the fore-arm member A, I mount a spring actuated ratchet-dog H, adapted to engage the teeth 30 on the ratchet-wheel G.

Upon the shaft E, I secure a collar J, which is provided with a binding-screw j, by means of which the collar J, may be secured 35 against rotation on the shaft E, said collar J, being provided with an arm J'. Secured in the arm J', is a cord J², leading to a spring J³, the opposite end of which is secured to the inner surface of the fore-arm member A, so that said spring J³, will operate to normally retain the arm E', in the 40 position thereof shown in Fig. 5. To the arm E', is secured an operating cord D', which extends around a pulley d², within the arm member A', on the pivot a, and is attached 45 to the loop B', on the strap B, (see Fig. 2).

On the shaft E, at each side of the arm E', I mount arms K and K', which are provided with flanged ears k, and k', adapted to be alternately engaged by the rocking-ratchets F 50 and F', and pivoted in the outer ends of the arms K and K', are adjustable fastenings L and L', for the finger operating cords D² and D³, the cords D², and D³, being secured 55 to the parts L and L', by means of the screw-sleeves l.

Fig. 9 shows the cords D² and D³, extending into the hand member A⁴, and attached to the finger controlling mechanism T, which is fully shown and described and 60 claimed in an application of even date herewith. From the terminal loop C', on the strap C, (see Fig. 2) a cord D⁴, extends over pulleys d³, and d, into the fore-arm member A, and terminates in the wrist swivel locking mechanism thereof, which is partic- 65

ularly shown, described and claimed in the said application of even date herewith.

The wrist swivel operating bar a², in this case extends from the disk G², in the wrist mechanism, upward through the fore-arm member A, and is pivoted in the upper arm member A', by means of a pivot a¹, at one side of the hinge-pivot a, as shown in Fig. 4, so that when the elbow hinge is operated, the wrist mechanism will operate. 75

In operation, when it is desired to close the fingers of the hand member A⁴, by dropping the shoulder opposite to the maimed arm a strain is put on the strap B, which crosses upward from that shoulder and by a slight upward movement of the maimed shoulder, the strap B, in front of the maimed shoulder will pull upon the cord D', which passes from the terminal loop B', down through the fore-arm member A, and is secured in the swinging lever E', which movement on the cord D', causes the lever E', to swing upward. 80

In Figs. 4 and 5, the rocking-ratchets F, and F', are shown in the positions in which they rest when the arm E' has been returned to its normal position after moving the lever K, to the position thereof shown in Figs. 4 and 5. The positions of the mechanisms shown in Figs. 4 and 5, are substantially as 90

follows; viz.—The rocking-ratchet F, by reason of the rotation of the ratchet wheel G, and its hub G', one notch, by engagement with the dog H, the lower end of the 95

rocking-ratchet has been forced upward, out of a notch in the hub of the ratchet-wheel G, which movement of the lower end of said ratchet has depressed the upper end of the same so that the ratchet F, will pass underneath the flanged lip k, on the arm K. Now 100

when this cord D', is again pulled as hereinbefore described, the arm E', will swing upward on the shaft E, and the rocking-ratchet F', will engage the flanged lip k', on the arm K', and carry it upward therewith to a similar 105

position as that shown of the arm K, in Fig. 5, which movement of the arm K', will, through the parts L' and L', pull on the cord D², which passes down through the wrist mechanism and into the hand member A⁴, 110

where it is secured to and adapted to rotate the finger controlling mechanism T, for the purpose of closing the fingers of the artificial hand. This operation of the mechanism T, (see Fig. 9) will cause the cord D³, to be wound on said mechanism, which will cause 115

the arm K, to swing forward into the position thereof occupied by the arm K', in Fig. 5. When the tension on the cord D', is relaxed, the tension of the spring J³, causes 120

the arm E', to return to the normal position thereof shown in Fig. 5, which causes the ratchet-wheel G, to be engaged by the dog H, so as to turn the same one notch, which movement of the ratchet wheel G, and its 125

130

hub G', causes the lower end of the rocking-ratchet F', to be raised out of the notch g', on one side of the ratchet-wheel G, which depresses the upper end of said ratchet so that the same will pass underneath the flanged lip k', and the lower end of the rocking-ratchet F, will drop into one of the notches g', thereby permitting the upper end of said ratchet to swing outwardly so as to engage 5 the flanged lip k, on the arm K, and move it back again to the position thereof shown in Fig. 5, which movement will, through the adjustable parts L and l, pull on the cord D³, for the purpose of operating the finger 10 controlling mechanism to again open the fingers of the artificial hand, A⁴, which operation of the mechanism T, will draw the arm K', back to the position thereof shown in Fig. 5. It will therefore be seen that 15 20 every alternate pull on the cord D', will cause the finger mechanism to open and the other alternate pull on the cord D, will cause them to close.

The peculiar structure and arrangement 25 of the shoulder harness is not herein claimed, as it forms the subject matter of a separate application.

Therefore having shown and described the construction and operation of my invention 30 so as to enable others to construct and use the same, what I claim as new and desire to secure by Letters Patent is:

1. The combination in an artificial arm composed of fore-arm, wrist, and hand 35 members, of finger opening and closing mechanism mounted in the hand member, reversing mechanism in said artificial arm, power communicating means extending between said finger opening and closing 40 mechanism and said reversing mechanism, and power communicating means extending from said reversing mechanism upward, substantially as set forth.

2. The combination in an artificial arm, 45 adapted for use on an amputation above the elbow joint, of an upper arm socket member, harness mechanism adapted to secure the same on the arm-stump, a fore-arm member hinged to said socket member, and an operating cord secured to said fore-arm member and passing therefrom over the front of the lower end of the socket member and through and out of the rear thereof where it may be secured to an operating strap attached to said supporting harness, substantially as set forth.

3. The combination in an artificial arm, adapted for use on an amputation above the elbow joint of an upper arm-socket 50 member, harness mechanism adapted to secure the same on the arm-stump, a fore-arm member hinged on said socket member, an elbow-joint operating cord secured in said fore-arm member and passing through and 55 out of said socket member to and attached

to an operating strap secured to said supporting harness, a wrist member secured on said fore-arm member, a hand member secured on said wrist member, finger operating mechanism in said hand member, a finger opening and a finger closing cord secured to said finger operating mechanism and extending therefrom upward through the hand and wrist members into said fore-arm member, reversing mechanism mounted 70 in said fore-arm member to which said finger operating cords attached, and a cord secured to said reversing mechanism and extending therefrom to and attached to an operating strap secured to said supporting harness, 75 substantially as set forth.

4. The combination in an artificial arm, of a fore-arm member, wrist and hand members, finger opening and closing mechanism in said hand member, operating cords secured to said mechanism and extending therefrom upward into said fore-arm member, reciprocating cord supports mounted within said fore-arm member to which said operating cords are secured, reciprocating 85 ratchet mechanism mounted in said fore-arm member adapted to alternately engage and move one of said cord supports, spring mechanism to move said ratchet mechanism in one direction, and an operating cord to move the same in the opposite direction, 90 substantially as set forth.

5. In an artificial arm, the combination of a fore-arm member, a wrist member and hand member secured thereon, an oscillating arm mounted therein, a pair of spring pressed rocking-ratchets mounted thereon, ratchet-wheel mechanism mounted thereon adapted to alternately actuate said rocking ratchets, a spring pressed dog adapted to engage said ratchet-wheel mechanism at the end of each reciprocation of said oscillating arm, spring mechanism adapted to actuate said arm in one direction, a cord secured to said arm adapted to operate the same in the opposite direction, a pair of oscillating arms mounted in said fore-arm member adapted to be alternately engaged by said rocking ratchets, finger opening and closing mechanism in said hand member and finger actuating means secured to said oscillating arms and extending therefrom downward through said fore-arm, wrist and hand members to and secured to said finger opening and closing mechanism, substantially as set forth.

6. The combination in an artificial arm comprising a fore-arm, wrist and hand members, of an oscillating arm mounted therein, spring pressed rocking-ratchets mounted on said oscillating arm, ratchet-wheel mechanism mounted on said arm adapted to alternately operate said rocking ratchets, a spring pressed dog adapted to engage and operate said ratchet-wheel mechanism at the return end of each oscillation of said 125 130

arm, oscillating supporting arms mounted on a common axis with said first mentioned oscillating arm adapted to be alternately engaged by said rocking-ratchets, finger operating mechanism mounted in said hand member, power communicating means extending therefrom to said supporting arms, spring mechanism adapted to operate said first mentioned arm in one

direction and an operating cord adapted to operate the same in the other direction, substantially as set forth.

In testimony whereof I affix my signature, in presence of two witnesses,

WILLIAM T. CARNES,

Witnesses:

LANDRY HARWOOD,
FANNIE O. RUPERT.
